UNITED STATES PATENT OFFICE.

EDWARD A. RYON, OF PITTSBURGH, PENNSYLVANIA, ASSIGNOR TO FRED. W. SIE-MENS, OF WELLSBORO, PENNSYLVANIA.

GLASS-GRINDING MACHINE.

Application filed July 22, 1919. Serial No. 312,479.

To all whom it may concern:

Be it known that I, EDWARD A. RYON, a citizen of the United States of America, and a resident of Pittsburgh, Allegheny County, and State of Pennsylvania, have invented certain new and useful Improvements in Glass-Grinding Machines, of which the following is a specification, reference being had to the accompanying drawings, forming a part thereof.

My present invention relates to machines for forming bands or rings on glassware, such as tumblers or drinking glasses.

The objects of the invention are to provide a machine for this purpose which will be relatively simple and inexpensive, which will operate to quickly form the band or bands on the glassware and which will automatically adjust itself to inequalities in the surface of the glass.

Speaking generally the invention consists of a cutting wheel and a glass support relatively movable toward each other and also relatively movable angularly to bring the face of the glassware into parallelism with the working face of the cutting wheel.

Other features of the invention relate to the special mounting for the work support, to the means for gauging the work with respect to the cutting surface and to a quickly detachable self-adjusting support for the glassware.

All of these features will be more fully understood from the following specification and from the accompanying drawings, which illustrate the invention embodied in one of its practical forms.

In said drawings:

Figure 1 is a front view of the machine.

Figure 2 is an end view of the same,

Figure 3 is a top plan view, and

Figure 4 is a sectional elevation taken substantially on line 4-4 of Figure 1.

Referring now to said drawings, by reference characters, 5 designates a banding wheel, shown in the present disclosure as an abrasive wheel having a plurality of ridges for cutting a number of parallel bands and mounted on a shaft 6 supported in slidably adjustable boxes 7, which may be shifted with respect to the work by means of the screws 8. The cutter wheel shaft is

driven by suitable means, such as the pulley or pulleys 9 and belt 10.

The work, which is shown in the form of a tumbler or drinking glass 11, is carried by a support in the nature of a mandrel and consisting of a base plate 12 mounted on a shaft 13, and having an annular flange 14 to confine the rim of the glass, said shaft carrying a supporting disk 15 of yieldable material fitting inside the mouth portion of the glass and a second similar yieldable supporting disk 16, fitting the bottom portion of the glass. The first disk may be fastened on the shaft or arbor 13 by means of the pin 17 and the second disk 16 is shown as yieldable axially toward the base disk 15 by being slidably engaged on the arbor, there being a spring 18 interposed between the two disks and a shoulder provided by the pin 19 at the outer end of the arbor to limit the outward movement of the second disk. In use the tumbler is slipped over the end of the arbor and as the outer disk fits the inner periphery of the bottom portion of the glass, it is carried along with the glass in the manner indicated in Figure 1, the inner fixed disk yieldably fitting the inner periphery at the mouth portion of the glass and the rim of the glass being confined within the annular flange 14 of the base plate 12. The whole thus constitutes in effect a yieldable and self-adjusting arbor for the glass. The glass is shown as removably held in position on said arbor by means of a freely rotatable pressure foot 19, carried by the adjusting screw 20, which is mounted in the lever 21 pivoted at 22 on the supporting arm 23 and yieldably held and engaged with the bottom of the glass by the spring 24.

In the present disclosure the glass support is the member which is movable to effect the engagement of the cutter and the glassware. The arbor or shaft 13 is for this purpose journaled in a block 25 pivotally mounted on the upper end of a post 26, which is supported by a suitable boxing 27 on the rock shaft 28. This rock shaft is supported in suitable bearings 29 and it will be clear that this construction enables the glass support to be swung bodily toward

and away from the cutter and also to be swung at an angle, as indicated in Figure 3 to bring the face of the glass into engagement with the working face of the cutter. 5 The shaft 13 is shown as driven by the belt 30 and pulley 31. A thrust bearing is shown as provided at 32 to take up the thrust of the spring pressed holding member 19 and the arm 23 which supports this member is shown directly attached to the movable bearing 25 of the arbor, so as to follow the movement of said bearing and arbor. 10

Adjustable stops 33 and 34 are shown provided on the rock shaft, which can be set 15 to engage the bearings 29 to thus determine the longitudinal adjustment of the rock shaft and hence the position at which the band or bands will be applied to the work. Cooperating stops 35 and 36 are shown provided 20 on the base 37 and arbor 13, respectively to limit the outward swinging movement of the arbor mechanism.

Means are provided in this invention for supporting and guiding the work at a point 25 or points adjacent to the cutting wheel. These supports consist in the present disclosure of the wheels or rollers 38 disposed at opposite sides of the cutting wheel in position to engage the surface of the end 30 portions of the sides of the glass as it is pressed toward the cutter, said rollers being pivotally carried by the spring pressed plungers 39 telescopically engaged in the supports 40, which are shown as pivotally 35 supported on the frame at 41, so as to be angularly movable with respect to the work.

In operation the work is slipped on the mandrel where it is held by the spring 40 pressed holder described. The work support is then shifted toward the cutter, as by grasping the bearing 25 by hand and in said shifting movement the mandrel is turned to bring the face of the work into substantial parallelism with the cutting face. This 45 adjustment is facilitated and in fact made substantially automatic by the engagement of the face of the work with the yielding supporting rollers, which, as shown, normally stand out beyond the rim of the cutting wheel so as to engage the face of the work and to recede as the work is pressed 50 against the cutting wheel. The pressure of these rollers is adjusted so that they will exert their force to hold the face of the work in substantial parallelism to the face of the cutter. These work supporting and guiding rollers adjust themselves to the irregularities 55 in the surface of the glass, permitting the glass to come into proper engagement with the cutting wheel at all points, the depth of 60 the cut being determined wholly by the pressure exerted on the mandrel.

From the foregoing it will be seen that 65 the machine is relatively simple and is designed to automatically take care of ir-

regularities in the surface of the glass and such variations as would ordinarily occur in the size of the glass. The machine also, it will be noted, is readily adjustable in regard to the position of the bands, and in 70 the relation of the cutter to the work support.

What I claim is:

1. In a glass banding machine, a cutting member, a swinging support movable toward 75 and away from said cutting member and a rotatable work holder pivotally mounted on said swinging support and thereby adjustable to vary the angle of the face of the work with respect to the face of the cutting member, and yieldable means at the side of the cutting wheel for engaging and supporting the work as it is pressed against the cutting wheel.

2. In a glass banding machine, a cutting 85 member, a swinging support movable toward, and away from said cutting member, and a rotatable work holder pivotally mounted on said swinging support and thereby adjustable to vary the angle of the face of the work 90 with respect to the face of the cutting member, and yieldable supports at opposite sides of the cutting wheel for engaging the face of the work at opposite sides of the wheel as the same is pressed against the 95 wheel.

3. In a glass banding machine, a cutting member, yieldable supports at opposite sides of said member and projecting in a plane to engage the face of the work which is brought 100 into engagement with the cutting member to thereby guide and yieldingly support said work, and a work support movable to carry the work into engagement with said yieldable supports.

4. In a glass banding machine, a cutting member, a work supporting member, one of 110 said members being relatively movable with respect to the other member to bring the face of the work into engagement with the cutting member, and a yieldable gauge and support for the work comprising a spring pressed yieldable roller positioned to engage the face of the work as the work is engaged with the cutter.

5. In a glass banding machine, a cutting member, a work supporting member, one of 120 said members being relatively movable with respect to the other member to bring the face of the work into engagement with the cutting member, and a yieldable gauge and support for the work comprising a spring pressed yieldable roller positioned to engage the face of the work as the work is engaged with the cutter, and said yieldable roller 125 being movable angularly with respect to the face of the work.

6. In a glass banding machine, a cutting member, a work supporting member, one of 130 said members being relatively movable with

respect to the other member to bring the face of the work into engagement with the cutting member, and a yieldable gauge and support for the work comprising a roller positioned to engage the face of the work as the work is engaged with the cutter, and a spring pressed telescopic support for said roller.

7. In a glass banding machine, a longitudinally slidable rock shaft, stops for limiting the sliding adjustment of the rock shaft, a rotatable glass holder pivotally supported

on said rock shaft, and a cutter positioned to be engaged by the work carried by said holder.

8. In a glass banding machine, a cutter, a work-holder movable toward said cutter, a yieldable work-engaging support at the side of said cutter, said yieldable support being angularly movable with respect to the work.

In witness whereof, I hereunto set my hand this 18 day of July, 1919.

EDWARD A. RYON.
